UNITED STATES PATENT OFFICE.

SAMUEL M. SCHWAB, JR., OF NEW YORK, N. Y.

DESIGN FOR A DECORATIVE FABRIC.

SPECIFICATION forming part of Design No. 21,734, dated July 26, 1892.

Application filed June 27, 1892. Serial No. 438,215. Term of patent 7 years.

To all whom it may concern:

Be it known that I, SAMUEL M. SCHWAB, Jr., a citizen of the United States, residing at New York city, in the county and State of New York, have invented and produced a new and original Design for a Decorative Fabric, of which the following is a specification, reference being had to the accompanying drawing, forming a part thereof, which represents a plan view of a piece of bunting or fabric decorated in accordance with my design.

The design consists of a series of contrasting panels and figures arranged upon the panels simulating stars and the flag of the United States, the figures of the stars and flags being alternately arranged.

As a minor feature of the design the panels are made in groupings of three and in the center panel the stars are arranged in groups, each group consisting of a star larger than the stars in the side panels and a series of small stars practically surrounding the large ones.

I claim—
The design for a decorative fabric, substantially as herein shown and described.

SAMUEL M. SCHWAB, JR.
